COMPARTMENTED FOOD CONTAINER OR THE LIKE

John Donald Bostrom, Niles, Ill., assignor to Poster
Packaging, Inc., Chicago, Ill., a corporation of Delaware

Filed Dec. 15, 1961, Ser. No. 67,926

Term of patent 14 years

(Cl. D58—13)

FIG. 3.

FIG. 4.

FIG. 1.

FIG. 2.

The broken line showing is for the purpose of illustration only.

The design is characterized by flattened longitudinal portions on top and bottom above a line tangential to separated rounded compartments, all as shown.

I claim:

The ornamental design for a compartmented food container or the like, as shown and described.
